UNITED STATES PATENT OFFICE.

EDGAR MOTT BOTTOOME, OF MOUNDSVILLE, WEST VIRGINIA, ASSIGNOR TO FOSTORIA GLASS COMPANY, OF MOUNDSVILLE, WEST VIRGINIA, A CORPORATION OF WEST VIRGINIA.

DESIGN FOR AN ARTICLE OF MANUFACTURE.

52,301.

Specification for Design.

Patented Aug. 27, 1918.

Application filed December 31, 1917. Serial No. 209,803. Term of patent 3½ years.

To all whom it may concern:

Be it known that I, EDGAR MOTT BOTTOOME, a citizen of the United States of America, and resident of Moundsville, county of Marshall, and State of West Virginia, have invented an original and ornamental Design for an Article of Manufacture, of which the following is a specification, reference being had to the accompanying drawings, in which—

Figure 1 is a side elevation of a drinking glass illustrating the new design; and—

Fig. 2 is a similar view taken at right angles to the viewpoint in Fig. 1.

The design consists of the ornamental configuration which is shown in the drawings as applied to a drinking glass of conventional form. The design is also applied to drinking glasses of other shapes and to dishes, vases and similar glass articles.

I claim—

The ornamental design for an article of manufacture, substantially as shown.

EDGAR MOTT BOTTOOME.
